Letters Patent No 486 Dated Aug 10th 1852

The schedule referred to in these Letters Patent and making part of the same

To all whom it may concern:

Be it known that I, Jacob Beesley, of the City of Philadelphia, in the County of Philadelphia, and State of Pennsylvania, have invented or produced a sett of new and original designs to ornament a stove called Complete Cook, and I do hereby declare that the following is a full & exact description of the same.

Fig 1 Represents a front plate, it is ornamented around the edges with a series of beads & square and ovolos at each end a quarter bead as at a, a, about the centre of the plate along the lower line of beads is represented a skeleton vase as at b, from which starts a section of a glory as at c, at either edge of the base a series of scroll work is carved extending far out towards the ends of the plate and returning around & meeting at the top of the glory as at d, d, d, d, and within the bounds of the scroll work are the letters & figures Complete Cook of 1852, at each of the top corners & extending inwards is a sprig of flower work and a scroll as at e, e, e, e.

Fig 2 Represents the oven door and is ornamented around the edge with bead work, ovolos & squares from the centre of the lower beads a skeleton vase as f, from which extends a section of a glory as at g, from either edge of the vase, starts scroll work running partially round the plate and meeting at the top as at h, h, h, h.

Fig 3 Represents the side fire door & is ornamented with bead work, ovolos & squares around the edges & from the lower edge of the bead a low skeleton vase i, from which starts scroll work j, j, j, meeting at the top around a section of a glory k.

Fig 4 Represents one of the front doors and is
